UNITED STATES PATENT OFFICE.

FELIKS BORUCZ, OF WILKES-BARRE, PENNSYLVANIA.

SHIP-PROTECTOR.

1,277,369.

Specification of Letters Patent.

Patented Sept. 3, 1918.

Application filed December 21, 1917. Serial No. 208,283.

To all whom it may concern:

Be it known that I, FELIKS BORUCZ, a citizen of Russia, residing at Wilkes-Barre, in the county of Luzerne and State of Pennsylvania, have invented certain new and useful Improvements in Ship-Protectors, of which the following is a specification.

This invention relates to certain new and useful improvements in ship protectors.

- 10 The primary object of the invention is the provision of a protector for ships adjustably arranged upon the hull thereof for positioning at the proper height to correspond with the draft of the ship.
- 15 A further object of the invention is to provide a missile shield for ships adapted for arrangement in the water surrounding the ship and readily adjustable to any height from points within the hull so as to arrange
- 20 the shield at all times adjacent the water level under varying load conditions of the ship, shock absorbing means being also arranged for the device.

- 25 A still further object of the invention is the provision of a protector for a ship arranged for vertical adjustment upon the hull thereof surrounding the latter and substantially vertically positioned, the device being light in weight and readily operable internally of the hull.

In the drawings, forming a part of this application and in which like designating characters refer to corresponding parts throughout the several views,

- 35 Figure 1 is a top plan view of a ship provided with my device.

Fig. 2 is an enlarged vertical sectional detail view through a side portion thereof.

- 40 Fig. 3 is a vertical sectional view taken upon line III—III of Fig. 2, and

Fig. 4 is a sectional view of the same taken upon line IV—IV of Fig. 2.

- 45 My invention broadly consists of a screen or guard 10 surrounding a ship such as 11 adjustably mounted upon the hull 12 thereof, the said guard being normally positioned substantially vertical in parallelism with the adjacent side of the hull. Upright U-shaped brackets 13 are carried in spaced relations
- 50 by the hull 12 having longitudinal slots 14 in their outer side or plate portion 15 while a screw 16 is journaled for rotation within each bracket 13 inwardly of the slot 14 thereof. The screw 16 at its lower end is swivelly
- 55 mounted in a block 17 and is journaled in a lug 18 adjacent its upper end while a pinion

20 carried by an operating shaft 21 journaled through the side of the hull 12 meshes with the gear 19 secured on the upper end of the screw 16.

60

A block 22 is arranged within the slot 14 adapted for sliding movement therein and has the screw 16 threaded through the inner end thereof. A flange 23 is carried by the block 22 slidably engaging the inner face of

65

the bracket plate 15. A shock absorbing traveler 24 for the guard 10 is carried by the block 22 and bracket 13 which includes a tube 25 secured to the outer end of the block

70

22 by means of a cotter pin 26 and provided with a flange 27 slidably arranged upon the bracket plate 15. An arm 28 is attached to the upper edge of the guard 10 and has a head 29 slidably positioned within the tube

75

25 while a shock absorbing spring 30 is tensioned between the block 22 and the said head 29. A perforated plug 31 is arranged within the outer end of the tube 25 with the arm 28 slidably arranged therethrough.

80

Two leg braces 32 are carried by the tube 25 supporting an axle 33 upon which rollers 34 are mounted which travel upon the portions of the plate 15 at the opposite sides of the slot 14. An adjustable strut 35 is connected between the lower edge of the guard 10 and the arm 28 arranged with a turn-buckle 36 whereby the guard may be stretched and

85

maintained substantially vertical:

90 From this detailed description of the invention, it will be understood that by revolving the shaft 21 from a point within the hull 12, the block 22 may be moved either up or down as desired for altering the position of the traveler 24 and the guard 10. The guard 10 entirely surrounds the hull 12 and in this manner the same may be positioned at any desirable point adjacent the water-line thereof so as to protect the hull from oncoming missiles at points where such missiles are most likely to travel. A torpedo 100 striking the guard 10 will have the force of its impact cushioned by the shock absorbing springs 30 which will prevent the torpedo from exploding so that the ship will be protected. The guard 10 may be arranged at the required distance from the hull 12 so as to render any explosion ineffectual in damaging the ship if this is found desirable. A curved outwardly projecting lip 37 at the bottom of the plate 15 forms a 105 limiting stop for the downward movement of the traveler by being positioned within

110

the path of movement of the rollers 34. The device is readily adjusted by any desirable means, not shown, for turning the shafts 21 of each of the travelers 24 from points within the hull 12 so that the shock absorbing protector or missile guard 10 may be arranged where the same will be most effective.

What I claim as new is:—

1. A protector adapted for mounting upon the hull of a ship comprising brackets arranged in spaced relations upon the hull, operating screws journaled within said brackets, actuating shafts for the said screws extending inwardly of the hull, vertically movable travelers carried by the brackets operatively connected with said screws and a missile screen carried by the said travelers encircling the hull when operatively arranged.
2. A protector adapted for mounting upon the hull of a ship comprising brackets arranged in spaced relations upon the hull, operating screws journaled within said brackets, actuating shafts for the said screws extending inwardly of the hull, vertically movable travelers carried by the brackets operatively connected with said screws, tubes carried by said travelers, a missile screen

surrounding the hull arranged outwardly of said tubes, arms connected to said screens having heads upon their inner ends slidably arranged within said tubes and cushioning springs within the tubes in contact with said heads.

3. A mounting means for ship protecting screens comprising a bracket having its outer side arranged with a longitudinal slot with a stop lip at the bottom of the side, a screw journaled within said bracket inwardly of the slot, a block slidably arranged through said slot in threaded engagement with the screw, operating means for the said screw, a tube carried by the outer ends of said block slidably engaging the said bracket side, brace legs depending from said tube, rollers journaled upon said legs adapted for traveling upon said bracket side in the plane of said lip, a perforated plug in the outer end of said tube, a mounting arm slidably arranged through said plug, a head upon the inner end of said arm slidably arranged within the tube and a shock absorbing spring between the said block and head.

In testimony whereof I affix my signature.

FELIKS BORUCZ.
